UNITED STATES PATENT OFFICE.

OTTO W. HEISE, OF BRIDGEPORT, CONNECTICUT, ASSIGNOR TO MANNING, MAXWELL & MOORE, INCORPORATED, OF NEW YORK, N. Y., A CORPORATION OF NEW JERSEY.

RETARD DEVICE FOR BOURDON GAUGES.

Application filed August 27, 1921. Serial No. 496,088.

To all whom it may concern:

Be it known that I, OTTO W. HEISE, a citizen of the United States, residing at Bridgeport, county of Fairfield, State of Connecticut, cut, have made a certain new and useful Invention in Retard Devices for Bourdon Gauges, of which the following is a specification.

This invention relates to retard devices for Bourdon tube gauges.

The object of the invention is to provide a retard structure for a Bourdon tube which is simple, economical to manufacture, quickly and easily adjustable, and efficient in operation.

A further object of the invention is to provide a retard device in which retarding action is imposed upon the segment or connections intermediate the tube and the staff of the dial hand instead of being imposed directly upon the tube, thereby eliminating any spasmodic or erratic action of the pointer or dial hand due to the action of the tube when coming directly in contact with the retarding device.

The invention consists substantially in the construction, combination, location and relative arrangement of parts, all as will be more fully hereinafter set forth as shown in the accompanying drawing, and finally pointed out in the appended claims.

Referring to the accompanying drawing,

Fig. 1 is a view in front face elevation, parts broken off, showing a Bourdon tube retard structure embodying my invention;

Fig. 2 is a view in section on the line 2—2, Fig. 1, looking in the direction of the arrows;

Fig. 3 is a fragmentary detail illustrating one form of retard spring embodying the principles of my invention; and

Fig. 4 is a broken detail view in section illustrating a modified form of retard spring embodying the invention.

It is one of the purposes of this invention so to position the retarding device that its effect is imposed upon the connections between the tube and the pointer. In practice it has been found convenient to arrange the retarding spring in the path of the segment which is geared to the staff of the pointer or dial hand.

In the accompanying drawing 5 designates the Bourdon tube, 6 the socket piece to

which one end of the tube is connected, 7 the spindle or staff for the dial hand or index which is journalled in the frame 8 supported by the socket 6. The usual hair spring 9 is connected to the staff 7. A rocking segment 10 pivotally mounted in the frame meshes with the pinion 11 on the staff 7 for turning the spindle or staff. The segment 10 is connected in the usual manner through linkage devices 12 to the free end of the Bourdon tube 5. A stud 15 is journalled to turn in an opening in the frame 8, the axis of the stud being substantially parallel to the axis about which the segment turns. This stud fits tightly in the opening so that it will remain indefinitely in any position of angular adjustment to which it may be turned. Preferably the stud is provided at one end with a slotted head 16 permitting the application of a screw driver for turning it. A coiled spring 13 is secured to the other end of the stud, the axis of the coil being eccentric to that of the stud, so that when the stud is turned the spring is shifted bodily in a direction transverse of its axis. The stud with the spring is so disposed that the free end of the spring extends transversely across the path of the segment 10 so that after a predetermined movement of the latter it encounters the spring and is resiliently retarded thereby.

In the modification shown in Fig. 4 a substantially straight elongate wire spring 14 is employed. This spring is also mounted eccentric to the axis of the stud and extends across the path of the segment.

It will be seen that the spring retarding device may be very easily adjusted so as to be set at the required retarding point by turning the stud 15. It is obvious that the retarding device whether in the form of a coil or in the form of an elongate flexible wire, or spring, may be adjusted by slightly bending the same more or less away from or towards the axis of the segment and in the direction of the length of the side of the segment, as indicated in dotted lines at 17, in Fig. 4, in order to vary the point at which it is engaged by the edge of the segment.

In practice a coiled spring is advantageous for use in high pressure retard gauges, for the reason that it is less liable to become permanently set by imposing the force of an abnormally applied pressure thereon, and furthermore, a larger size or diameter of

wire may be employed, which renders the device more sturdy and rugged.

The adjustment for various amounts of travel for an identical initial pressure exerted by the Bourdon tube, or for an identical travel for variations of the initial pressure exerted by the tube, may thus be made either by bending the retard spring away from or towards the axis of the seg-
10 ment.

It will be observed that the strain of the impact is taken by the bearings of the segment, and that variations, if any, imposed upon the path of travel of the free
15 end of the Bourdon tube by reason of the resistance of the retarding spring, have no effect in causing spasmodic, erratic or inefficient movements of the dial hand or pointer.

Having now set forth the objects and na-
20 ture of my invention, and a construction embodying the principles thereof, what I claim as new and useful and of my own in-
vention and desire to secure by Letters Pat-
ent is:

25 1. A pressure gauge having a pressure response element, a movable index, connections for transmitting movement from the pressure responsive element to the index comprising a movable part, a bodily adjust-
30 able elongate spring extending transversely across the path of movement of the movable part, and means constraining the spring during adjustment thereof to move bodily in a fixed and predetermined path transverse of
35 its longitudinal axis, said means comprising a movable member fixedly connected to the spring, and a fixed member delimiting movement of said movable member.

40 2. A pressure gauge having a Bourdon tube, a movable index, connections comprising a rocking segment for transmitting movement from the tube to the index, an elongate spring extending transversely across the path of movement of the seg-
45 ment, and a normally fixed but rotatable support to which one end of the spring is fixedly secured and by means of which the spring may be bodily shifted, said support being provided with a slot for the reception
50 of a screw driver for turning it.

3. A pressure gauge having a Bourdon tube, a movable index, connections compris-

ing a rocking segment for transmitting movement from the tube to the index, an elongate spring extending transversely
55 across the path of the segment, and a nor-
mally stationary rotatably adjustable stud having its axis substantially parallel to that of the sector, one end of the spring being supported upon the stud eccentrically to the
60 latter.

4. A pressure gauge comprising a Bour-
don tube, a rocking segment connected thereto, an index actuated by the segment, a stud
65 arranged to turn about an axis substantially parallel to that of the segment, said stud normally being fixed in position, and a heli-
cal spring having one end secured in eccen-
tric position to one end of the stud, said
70 spring extending transversely across the path of the segment and being unsupported at its opposite end.

5. A pressure gauge having a pressure re-
sponsive element, an index actuatable thereby,
75 and means operative upon the attainment of a predetermined pressure for retard-
ing the pressure responsive element comprising a part movable by the pressure re-
sponsive element, a bodily adjustable elong-
ate spring extending transversely across
80 the path of movement of said movable part,
and means constraining the spring during
adjustment to move bodily in a fixed and
predetermined path transverse of its longi-
tudinal axis, said means comprising a mov-
85 able support upon which the spring is
mounted, and a fixed member having a bear-
ing for the reception of the support.

6. A pressure gauge having a pressure re-
sponsive element, an index actuatable thereby,
90 and means operative upon the attainment of a predetermined pressure for retarding the pressure responsive element comprising a part movable by the pressure responsive ele-
ment, a support turning in a fixed bearing,
95 and an elongate member mounted eccentrically upon the support and turning there-
with, said member extending transversely
across the path of the said movable part.

In testimony whereof I have hereunto set
my hand on this 19th day of August A. D.,
1921.

OTTO W. HEISE.
